CLAIM

The ornamental design for a foodstuff mill or replica thereof, as shown and described.

DESCRIPTION

FIG. 1 is a top isometric view of a foodstuff mill or replica thereof in accordance with the present design;

FIG. 2 is left side view thereof, the right side view being a mirror image of the left side view;

FIG. 3 is a front view thereof;

FIG. 4 is a top view thereof; and,

FIG. 5 is bottom view thereof.

The dash-dash broken lines illustrate portions of a foodstuff mill or replica thereof that form no part of the claimed design. The dot-dash-dot broken line illustrates a boundary of the claimed design that forms no part of the claimed design.
